UNITED STATES PATENT OFFICE

JACOB A. SCHOEDINGER, SR., OF MIAMI, FLORIDA

DESIGN FOR A TIRE

Application filed January 30, 1933. Serial No. 47,051. Term of patent 14 years.

To all whom it may concern:

Be it known that I, JACOB A. SCHOEDINGER, Sr., a citizen of the United States, residing at 325 N. W. 45th Street, in the city of Miami, county of Dade, State of Florida, have invented a new, original, and ornamental Design for a Tire, of which the following is a specification, reference being had to the accompanying drawing, forming part thereof.

Fig. 1 is a plan view of a section of a tire of my design.

Fig. 2 is a side elevation of the same, and Fig. 3 is a transverse section on the line 3—3 of Fig. 1.

Fig. 4 is a perspective view, a section being illustrated in solid lines.

I claim:

The ornamental design for a tire as shown.
JACOB A. SCHOEDINGER, Sr.
